UNITED STATES PATENT OFFICE.

ADOLPH H. SCHMEDTJE, OF ST. LOUIS, MISSOURI, ASSIGNOR OF ONE-HALF TO JOHN SCHMEDTJE, OF ST. LOUIS, MISSOURI.

BOTTLE-STOPPER.

SPECIFICATION forming part of Letters Patent No. 792,352, dated June 13, 1905.

Application filed July 1, 1904. Serial No. 214,841.

To all whom it may concern:

Be it known that I, ADOLPH H. SCHMEDTJE, a citizen of the United States, residing at St. Louis, State of Missouri, have invented certain new and useful Improvements in Bottle-Stoppers, of which the following is a specification containing a full, clear, and exact description, reference being had to the accompanying drawings, forming a part hereof.

My invention relates to improvements in bottle-stoppers; and it consists of the novel features herein shown, described, and claimed.

My object is to provide a beer-bottle or the like with a permanent stopper and seal; and my invention consists of the combination, with a beer-bottle or the like having a neck tapering outwardly, the discharge end of the neck being ground, of a stopper tapering both ways from its center and ground to fit in the ground portion of the neck and form a stopper and seal.

In the drawings, Figure 1 is a vertical central section of the neck of the bottle and showing my stopper in position for use. Fig. 2 is a perspective of the bottle-stopper.

Referring to the drawings in detail, my improved bottle-stopper comprises a solid glass body beveled both ways from its center and ground to form the finished tapered ends 3 and 4. Annular grooves 5 and 6 may be formed at the tips of the ends 3 and 4 to provide means whereby the stopper may be gripped for handling. The bottle-neck 7 tapers outwardly, and the discharge end of the neck has a tapered opening 8, ground and finished to receive either of the tapered ends 3 or 4 of the stopper.

The stopper is inserted into the bottle during the operation of forming the bottle and cannot be removed after the bottle is completed, except by breaking the glass.

In filling the bottle suitable instruments may

be inserted to hold the stopper out of the neck and the bottle inverted and filled, and then the stopper is allowed to drop into place. 45 The object of having the finished ends is to provide means of allowing the stopper to drop either end up.

The stopper fits tightly in its seat in the neck of the bottle and forms a perfect stopper 50 and seal, no other seal being required to make the bottle air and water tight. When the stopper is seated, it extends to the upper end of the neck of the bottle and is readily accessible when it is desired to open the bottle, and a slight tap with any suitable instrument upon 55 the upper end of the stopper will unseat it and cause it to fall down into the bottle.

I claim—

1. The combination with a bottle, the neck 60 of which is internally ground and finished to form a tapered seat at its discharge end, of a stopper confined within the bottle and ground and finished therein so that it is adapted to fall into said seat and seal the said neck upon 65 the bottle being inverted, substantially as set forth.

2. The combination with a bottle the neck of which tapers outwardly and the outer end of said neck being ground and finished to form 70 a seat, of a stopper tapering both ways from its center and confined within the bottle, and also ground and finished therein at both its ends, so that either of the finished ends of the stopper may fall into the said seat when 75 the bottle is inverted, substantially as set forth.

In testimony whereof I have signed my name to this specification in presence of two subscribing witnesses.

ADOLPH H. SCHMEDTJE.
